CLAIM

The ornamental design for a combined portable hose reel and hose therefor, as shown or described.

DESCRIPTION

FIG. 1 is a front, partial top and right side perspective view of a combined portable hose reel and hose therefor showing our new design;

FIG. 2 is a front elevational view thereof;

FIG. 3 is a right side elevational view thereof;

FIG. 4 is a rear elevational view thereof;

FIG. 5 is a left side elevational view thereof; and

FIGS. 6 and 7 are respectively top and bottom plan views thereof.

FIG.1

FIG. 3

FIG. 2

FIG. 6

FIG. 7
